UNITED STATES PATENT OFFICE.

THOMAS KEITH LEGARÉ, OF COLUMBIA, SOUTH CAROLINA.

ADJUSTABLE CROWN-TEMPLET.

1,093,867

Specification of Letters Patent. Patented Apr. 21, 1914.

Application filed June 29, 1912. Serial No. 706,804.

To all whom it may concern:

Be it known that I, THOMAS KEITH LEGARÉ, a citizen of the United States, residing at Columbia, Richland county, State of South Carolina, have invented certain new and useful Improvements in Adjustable Crown-Templets, of which the following is a specification.

This invention relates to road templets and has for its object the provision of a templet which may be conveniently used for the purpose of readily setting stakes to serve as guides in forming the crown of the roadway.

15 It has been heretofore necessary in order to determine the surface of a roadway to have a surveyor set the stakes to show the elevations of the different parts of the roadway. This is comparatively slow and correspondingly expensive work and it is the object of this invention to provide a means by which the foreman of a road construction gang or other person of ordinary skill may quickly and accurately set the stakes without the services of a surveyor.

The novel features of the invention will be apparent from the following description taken in connection with the accompanying drawings, in which:

20 Figure 1 is a side elevation of a templet embodying the invention. Fig. 2 is an enlarged section on the line 2—2 of Fig. 1. Fig. 3 is an enlarged side elevation of one of the gages. Fig. 4 is a transverse section of a roadway showing a templet extending from one curb to the other. Fig. 5 is a view similar to Fig. 4 and showing the use of a templet to span one-half of the distance between the curbs. Fig. 6 is a view similar to Fig. 4 and showing the use of two templets to span one-half the distance between the curbs.

25 Referring to the drawings the templet will be seen to comprise a horizontal beam 10, which may be made of wood or any suitable metal, having mounted thereon a plurality of gages 11. I have shown and prefer to use five of the gages 11, but it will be understood that any other suitable number may be employed. The gages are preferably spaced apart equal distances and secured in suitable guides 12 arranged on the beam 10. Cross pieces 13 and 14 are secured to the upper and lower ends of the guides and hold the gages in the guides, and serve as an index in connection with the scale on the

gages hereinafter described. Each of the gages is provided with a longitudinal slot 15 extending the greater portion of the length thereof, and bolts 16 are arranged in the beam 10 and pass through the slots 15 in the gages and are provided with suitable washers 17 and nuts 18 whereby the gages may be clamped to the beam 10. Each of the gages carries a scale 19 which may be a standard metal scale divided into eighths, quarters and halves of an inch.

30 Referring to Fig. 4 the curbs of the road are shown at *a* and a single templet is shown as extending from one curb to the other. As will be seen from Fig. 3 the scales extend upwardly from the lower ends of the gages and the height of the crown of the road above the level at the curb may be determined by adjusting the end gages *b* so that the lower edge of the beam 10 will be at the mark on the scale 19 which indicates the height of the center or crown of the road above the elevation at the curb.

In order to secure accuracy the templet 35 may be provided with suitable spirit levels 20 adjacent the ends thereof whereby the beam 10 may be set in a perfectly level position.

40 In order to determine the heights of the roadway at points between the curb and the center the intermediate gages may be set so that the lower edge of the beam 10 registers with the proper mark on the scale 19. When the gages have been set to their proper position the templet may be moved from one position to another along the roadway and stakes driven to correspond with the lower ends of the gages, thus obviating the necessity for a surveyor to set each stake by means 45 of a surveying instrument.

45 In Fig. 5 I have shown a templet which extends from the curb to the center or crown of the road. This arrangement is designed for use in roads which are much wider than that shown in Fig. 4. In this case the gage *b* at the curb of the road is set to show the proper elevation of the crown above the level at the curb and the intermediate gages are set to indicate the proper curvature. By 50 this arrangement it is possible to accurately determine the surface of the roadway as the beam 10 may be leveled by means of the spirit levels 20.

55 In Fig. 6 I have shown an arrangement for use on a very wide road. In this arrangement two templets may be used and

stakes set for one side of the road at a time or four templets could be used to span the whole width of the road. One end of one of the templets in this arrangement is set at the curb and the other end at a point one quarter of the distance across the road. The second templet is arranged at the end of the first and extends to the center of the road. Or, if desired one templet can be used in this arrangement for the entire operation by first setting the stake for one quarter of the roadway and then simply changing the position of the gages and moving the templet over to the next quarter. Thus only one templet is necessary to secure all points on any height of crown of any width of roadway.

In order to render the use of the templets more convenient tables may be prepared showing the various positions to which the gages should be set in order to give different degrees of crowning to the road and with such tables it is possible to quickly set the

templets and locate the stakes for a long section of roadway.

Having thus described the invention what is claimed is:

In a stake setting templet, the combination of a beam, leveling means secured thereon, a plurality of gages adjustable in the same direction transversely of said beam, means on the beam constituting an index for each of said gages, measuring scales on each of said gages adapted to indicate the relation of the ends thereof, on the same side of said beam, to said indexing means, and means for independently securing each of said gages in different positions on said beam.

In testimony whereof I affix my signature in presence of two witnesses.

THOMAS KEITH LEGARÉ.
